Term of patent 14 years

(Cl. D44—1)

Fig. 1.

Fig. 2.

Fig. 3.

Fig. 4.

Fig. 5.

Fig. 7.

Fig. 6.

FIG. 1 is a perspective view of a domestic food mixing and preparing base, showing our new design in an in-counter embodiment, a portion of a counter-top being shown in broken lines for illustrative purposes only;

FIG. 2 is a similar perspective view thereof with the beater driving arm in raised position;

FIG. 3 is a slightly enlarged scale perspective view thereof with the beater driving arm in folded position and with the bowl turntable removed;

FIG. 4 is a rear elevational view thereof;

FIG. 5 is a side elevational view thereof;

FIG. 6 is a perspective view of a domestic food mixing and preparing base showing our new design in an on-counter embodiment, with the beater driving arm in folded position and a bowl turntable omitted; and

FIG. 7 is a rear elevational view thereof.

The broken line showings of a beater and a bowl appearing in FIG. 2 and 5 are for illustrative purposes only.

The sides opposite those shown are substantially the same as those shown except for the omission of the appliance socket, control console recess and portions of control elements received within the control console recess which are all otherwise shown.

We claim:

The ornamental design for a domestic food mixing and preparing base, as shown and described.
